UNITED STATES PATENT OFFICE.

WILLIAM C. WATSON, OF PATERSON, NEW JERSEY.

CAR-COUPING.

SPECIFICATION forming part of Letters Patent No. 459,502, dated September 15, 1891.

Application filed May 20, 1891. Serial No. 393,438. (No model.)

To all whom it may concern:

Be it known that I, WILLIAM C. WATSON, of Paterson, in the county of Passaic and State of New Jersey, have invented a new and useful Improvement in Car-Couplings, of which the following is a specification, reference being had to the accompanying drawings.

This invention relates to that class of couplings the principal members of which are hooked draw-heads pivoted and having lateral movements within buffer-heads, the coupling action being effected by the engagement of two such hooked draw-heads, one on each of the cars to be coupled.

15 The invention consists in the construction hereinafter described and claimed.

The object of the improvement is twofold, viz: first, to afford greater flexibility of the coupling and thereby to reduce the liability 20 to breakage in turning a curve, and, second, to provide in a simple and effective manner for the operation of the coupling from the side, roof, or floor of the car, and to avoid the dangerous necessity of men having to go between 25 the cars to effect the coupling and uncoupling.

Figure 1 represents a horizontal sectional view of those parts of a coupling which are attached to one car and a plan view of portions of corresponding members attached to 30 another car. Fig. 2 is a vertical sectional section corresponding with the parts in section in Fig. 1. Figs. 3 and 4 are plan views representing portions of the couplings of two cars in different positions. Fig. 5 is a front view 35 of those members of the coupling attached to one car. Fig. 6 is a view corresponding with Fig. 1, showing the parts in a different position. Fig. 7 is a detail view which will be hereinafter explained.

40 Similar letters of reference designate corresponding parts in all the figures.

A is a buffer-head arranged under the car-body between guides *a a*, in which it is capable of moving lengthwise. This buffer-head 45 is hollow throughout and has an opening through its rear for the passage of the draw-bar B. Its front end, which projects from the car, is or may be of substantially similar form to that of other buffer-heads, except that it has 50 on one side a forward projection *l*, the object of which will be hereinafter explained.

C is the hooked draw-head, pivoted within

the rear portion of the buffer-head to the front end of the draw-bar B by a pivot *b*. The draw-bar B passes through a plate *B'*, secured to 55 the car-body D. Between this plate *B'* and the rear of the buffer-head there is applied around the draw-bar the coiled buffer-spring *c*, and between the said plate and a nut *d*, screwed onto the rear of the draw-bar, there 60 is applied around the said bar a coiled spring *c'*, which permits a longitudinal movement of the draw-bar relatively to the buffer-head when traction is applied to the draw-head. The pivot *b* is represented as passing through 65 slots *b'* in the top and bottom of the draw-head, the said slots permitting the longitudinal movement of the draw-head relatively to the buffer-head.

Between the outer side of the draw-head 70 C—that is to say, the opposite side to that on which its hook *11* projects—and the corresponding side of the buffer-head, which is that on which the projection *11* is provided, there is applied a spring *e*, which exerts a constant 75 tendency to throw the draw-head C into the coupling position shown in Fig. 1. On the opposite side of the coupling-head C is arranged an upright spindle *f*, which is pivoted within the draw-head, and which carries 80 within the draw-head a cam *g* for the purpose of throwing the said draw-head to the position for uncoupling, as shown in Fig. 6. The space provided within the buffer-head A is not, however, wide enough to permit a sufficient 85 lateral movement of its draw-head C to uncouple the hook thereof from the hook of the corresponding draw-head of the next car without the corresponding movement of the latter draw-head. This may be understood by reference to Fig. 6: The lower part of the spindle *f* projects below the draw-head and is squared to receive a lever *E*, which serves the purpose of turning the spindle to bring the cam *g* to the position shown in Fig. 1 to permit 90 the coupling, or to the position shown in Fig. 6 to effect the uncoupling. The ends of this lever are intended to project beyond or be accessible from the sides of the car for the purpose of working the coupling without going 95 between the cars, and one end of it passes through a slotted locking-plate *E'* for the purpose of locking the said lever with the cam *g* in the position shown in Fig. 6 for uncoupling.

ling. This locking-plate, which is shown in Figs. 1 and 5, and of which Fig. 7 is a side view, has in its slot h a notch h' , into which the lever is raised for the purpose of effecting this locking, and to provide for the lever entering and being disengaged from this notch it is fitted to the square of the spindle f in such manner that it may be capable of a sliding movement upward and downward. For the purpose of operating the spindle f and cam g from the platform or from the roof of the car I provide in suitable bearings i i' on the end of the car-body a spindle j , and on the lower end of this spindle I provide a crank-arm j' , which is connected by a crank-pin j^2 and a link j^3 with the lever E .

To illustrate the operation of my invention, I have shown in Figs. 3, 4, and 6 portions of a second coupling—that is to say, of a coupling belonging to another car—the buffer-head and the draw-head of this second coupling being respectively designated by A' and C' .

Referring now to Fig. 6, I will suppose that the lever E is brought to a position in which the cam g holds the draw-head C in the uncoupled position in which it is locked by the engagement of the lever in the notch h' of the locking-plate E' , and will suppose that the draw-head C' of the other coupling is similarly held and locked, the cars being then brought together, the two draw-heads being in the positions shown in Fig. 6. To effect the coupling the lever E is unlocked and turned to bring its cam g to the position shown in Fig. 1, and the corresponding lever of the other coupling is operated in the same way, and the engagement of the two hooks of the draw-head, takes place, as shown in Fig. 1. This engagement is maintained by the springs e of the two draw-heads in such manner that the connection between the cars is a very flexible one and well adapted for turning very short curves, as may be understood by reference to Figs. 3 and 4, which show the relative positions occupied by the members of the coupling on two cars of opposite direction. In this operation that buffer-head projection l which is on the inner side of the curve serves as a guard to prevent the disengagement of the hook of the draw-head which is on that side of the car. To effect the unlocking the lever E is moved to turn the spindle f and the cam g to the position shown in Fig. 6 and throw aside the hooked draw-head. The lever E is then lifted into the notch h' of the lock. The coupling of the adjacent car is to be worked in the same way to throw the draw-head C' to the corresponding position. The necessity of operating both the

hooked draw-heads to effect the uncoupling prevents any liability of an unintentional uncoupling taking place, for the coupling would keep the two cars coupled under most circumstances, even though the hooked draw-head of one car were in the uncoupling position shown in Fig. 6, provided that of the other car were left free by the cam g to the action of the spring e , and thereby brought to the coupling position.

What I claim as my invention, and desire to secure by Letters Patent, is—

1. The combination, substantially as herein described, of corresponding hollow buffer-heads, corresponding hooked draw-heads pivoted one in each buffer-head to swing laterally therein to such extent only that a lateral movement of either of said draw-heads alone would be insufficient to swing it clear of the other draw-head, and means, substantially as herein described, for swinging said draw-heads.

2. The combination, with a car-body, of a hollow buffer-head, a hooked draw-head pivoted to swing laterally within the said buffer-head, an upright spindle pivoted within the buffer-head, a cam on said spindle for moving aside the said hooked draw-head to produce the uncoupling, a lever on said spindle arranged crosswise of the car-body to be accessible from the sides thereof, a lock on one side of the car-body for locking said lever when the draw-head is uncoupled, and a spring for throwing the draw-head into coupling position when the lever is unlocked, all substantially as herein set forth. 95

3. The combination of a hollow buffer-head, a hooked draw-head pivoted to swing laterally within the said buffer-head, an upright spindle pivoted within the buffer-head, a cam fast on said spindle for throwing aside the said hooked draw-head, a lever on said spindle, a second spindle attached to the car-body, a crank on said second spindle, and a connection between said crank and lever, all substantially as herein set forth. 100

4. The combination, with the corresponding hooked draw-heads of two cars, of buffer-heads on the two cars, in which said draw-heads are pivoted to swing laterally and which have each a forward projection l at one side to limit the lateral movement of the hook of the other draw-head, substantially as and for the purpose herein set forth. 110
